UNITED STATES PATENT OFFICE.

DAVID H. LOVELESS, OF PROVO, UTAH, ASSIGNOR OF ONE-FOURTH TO
WALTER G. TAYLOR, ONE-FOURTH TO GEORGE TAYLOR, JR., AND
ONE-FOURTH TO JOHN J. LOVELESS, ALL OF PROVO, UTAH.

THILL-SUPPORT.

No. 823,424.

Specification of Letters Patent.

Patented June 12, 1906.

Application filed August 28, 1905. Serial No. 276,100.

To all whom it may concern:

Be it known that I, DAVID H. LOVELESS, a citizen of the United States, residing at Provo city, in the county of Utah and State 5 of Utah, have invented certain new and useful Improvements in Shaft or Thill Supports; and I do declare the following to be a full, clear, and exact description of the invention, such as will enable others skilled in the art 10 to which it appertains to make and use the same.

My invention relates to improvements in shaft or thill supports for vehicles; and it consists in the novel construction, combination, and arrangement of devices hereinafter 15 described and claimed.

The object of the invention is to improve and simplify the construction and operation of devices of this character, and thereby render the same more efficient and durable in 20 use and less expensive to manufacture.

The above and other objects are attained by means of the construction illustrated in the accompanying drawings, in which—

25 Figure 1 is a side elevation of the device, showing it applied to the shaft and axle of a vehicle. Fig. 2 is a plan view of the same. Fig. 3 is a perspective view of the keeper which is carried by the axle, and Fig. 4 is a 30 similar view of a slightly-modified form of keeper.

Referring to the drawings by numeral, 1 denotes the shaft, and 2 the axle, of a vehicle of any description, and 3 denotes my improved holding device, which is adapted to support the shaft, thill, or tongue in its elevated position, as shown. The device consists of a catch or latch 4, which is carried by the shaft 1, and a keeper 5, which is carried 35 by the axle and adapted to be engaged by the catch or latch 4. The catch 4 is preferably constructed of a single piece of resilient metal and is adapted to be adjustably secured upon the upper side of the shaft 1. As 40 shown, said latch has its rear end bent to form an S-shaped curve, which provides a resilient jaw 6, adapted to engage the loop of the keeper 5. The straight portion of the latch 4 is adjustably secured upon the shaft 1, 45 by means of the usual T-shaped bolts 7, which pass through longitudinally-disposed slots 8, formed in the latch, as shown. In or-

der to adjust the free end 6 of the latch to cause it to properly engage the keeper 5, I provide a tension-bolt 9, which has adjusting-nuts 11 upon its threaded end above and below the latch, whereby it may be adjusted, as will be readily understood. The keeper 5 (shown in Figs. 1 to 3, inclusive, of the drawings) is formed from a single piece of metal 50 rod by bending it to form a latch-receiving or keeper loop 12 and an attaching portion 13. The loop is of substantially U form and is disposed vertically at right angles to the open-slotted attaching portion 13, which latter is adapted to engage the under side of the axle 2. The keeper is secured upon the axle by means of a clip 14, which may, if desired, be the same one which secures the shaft or thill coupling upon the axle. This clip 14 is 55 of the usual U form and has its threaded ends 15 projecting through the opening or slot formed in the attaching portion 13 of the keeper, as will be readily understood. Instead of constructing the keeper 5 as just described, the same may be constructed as shown in Fig. 4 of the drawings. In this form it will be seen that the loop 12 is formed in the center of the piece of rod from which the keeper is formed, and both of its ends are 60 bent inwardly and rearwardly in parallel relation to form the attaching portion 13.

The use and advantage of the invention will be readily understood from the foregoing description, taken in connection with the accompanying drawings.

It will be seen that when the two members of the device are properly adjusted the latch or catch 4 will spring into the loop of the keeper 5 when the shaft or thill 1 is in its elevated position, as shown in Fig. 1 of the drawings. The frictional engagement of the curved end 6 of the latch with the top of the loop 12 is sufficient to support the weight of the shafts, and this engagement may be varied by adjusting the nuts 11 upon the bolt 9, as previously explained.

Owing to the simplicity of the construction it will be seen that the parts may be manufactured at a comparatively small cost and 100 may be quickly and easily applied to a vehicle of any description.

While I show and describe the device as used for supporting a pair of shafts or thills,

it will be understood that the same may also be used to support the tongue or pole of a vehicle.

Various changes in the form, proportion, 5 and the minor details of construction may be resorted to without departing from the principle or sacrificing any of the advantages of this invention.

Having thus described my invention, what 10 I claim as new, and desire to secure by Letters Patent, is—

1. A thill-support comprising a spring-latch secured on the upper side of a thill, projecting inwardly therefrom, and having its inwardly-projecting portions curved to form a resilient jaw, means to adjust said jaw toward, and from the pivot of the thill-coupling, and a keeper secured to the axle and having an upwardly-extended loop through

which said resilient jaw of the latch passes, 20 said jaw engaging the upper end of said loop.

2. A thill-support comprising a spring-latch secured on and longitudinally adjustable with reference to the thill and formed 25 with a curved resilient jaw projecting beyond the inner end of the thill, and a keeper secured on the axle and having an upwardly-extended loop through which the said resilient jaw of the loop extends, said jaw engaging the upper end of the said loop. 30

In testimony whereof I have hereunto set my hand in presence of two subscribing witnesses.

DAVID H. LOVELESS.
